UNITED STATES PATENT OFFICE.

LOUDOUN CAMPBELL, OF WASHINGTON, DISTRICT OF COLUMBIA, ASSIGNOR
OF ONE-HALF TO ROBERT J. THOMAS, OF ALEXANDRIA, VIRGINIA.

FIRE-ALARM APPARATUS.

SPECIFICATION forming part of Letters Patent No. 692,765, dated February 4, 1902.

Application filed June 10, 1901. Serial No. 63,908. (No model.)

To all whom it may concern:

Be it known that I, LOUDOUN CAMPBELL, a citizen of the United States, residing at Washington, in the District of Columbia, have invented certain new and useful Improvements in Fire-Alarm Apparatus, of which the following is a specification.

This invention relates to improvements in fire-alarm boxes adapted to detect and expose malicious persons while in the act of sending in a false alarm, and it comprises various means for sounding a local alarm before the box can be opened to send in a fire-alarm and means for preventing the immediate opening of the box after the local alarm is sounded in order that the person endeavoring to send in the false alarm may be detained for a few moments and detected in the act. The locking device upon the box may be adjusted by the proper authorities to cause any desirable period of delay in opening the box, and in order to expose the person attempting to send in an alarm at night means are provided for illuminating the immediate vicinity of the box before the key can be operated.

In the accompanying drawings, which illustrate the invention, Figure 1 is a front view of a fire-alarm box with my improvements attached and the alarm devices ready for action, the sliding door being removed and the whistle-chamber being shown in section. Fig. 2 is a section on the line 2 2 of Fig. 1. Fig. 3 is a horizontal section through a portion of the door and the locking device. Fig. 4 is a sectional view through the housing above the box, taken on the line 2 2 of Fig. 1, the illuminating-chamber being shown in central section and the alarm devices released. Fig. 5 is a front view of the same with the sliding door removed and the illuminating-chamber shown in central section. Fig. 6 is a detail showing the connections between the spring-actuated rods and the rod for lifting the top from the illuminating-chamber. Fig. 7 is a front view of a fire-alarm box of the kind having a fragile front provided with my improved locking device. Fig. 8 is a top plan view of the lock illustrated in Fig. 7, and Fig. 9 is a sectional view showing a whistle-alarm and means for operating the same which are different from those shown in Fig. 1.

Referring to Figs. 1 to 6, inclusive, of the drawings, A indicates a fire-alarm box, which may be of any ordinary construction and may contain the usual devices for sending in a fire-alarm to a distant station. Upon the inner face of the door 1 is arranged a sliding bolt 2, the forward end of which is adapted to pass in behind a lug 3 upon the side wall of the box. A spring 4, secured to suitable studs 5 and 6 upon the door and bolt, respectively, is adapted to retract the bolt when the latter is released from the locking devices. An opening 7 is formed in the bolt, and a similar opening 8 is formed in the door of the box, the latter forming a guide for a head 9, movable through the opening and having an inclined face 10, adapted to engage the shoulder 11 of the bolt and move the latter forward when the head is forced inwardly. A threaded stud 12 is connected with the head and projects outwardly beyond the outer face of the door. Surrounding the opening in the door is a casing 13, in the outer end of which is journaled a nut 15, having a threaded central opening 16, adapted to engage with the threads upon the stud, and a key or handle 17, flattened upon the sides, by which the nut may be turned. It will be seen that when the nut is turned the head 9 will be forced inward or outward, according to the direction of rotation of the nut. When the head is moved outward, the bolt will be retracted by the spring and the door may be opened, and when the head is moved inward the cam-surface 10, engaging the shoulder 11, will force the bolt outward into engagement with the lug 3. A stop-pin 18 is arranged upon the stud 12 within the casing 13 and adapted to limit the movement of the latter in order that the stud may not become disengaged from the nut or withdrawn from the guide-opening 8. In order to move the head through the entire length of its travel, it is necessary to turn the nut a number of times, and hence on account of the slow-acting unlocking mechanism thus provided it is impossible to instantly open the door and send in a fire-alarm. In practice the cam-head may be left in such position by the inspector that a single turn or any number of turns of the nut will release the bolt, and the time required for turning in a fire-alarm will be corre-

spondingly varied. The key or handle 17 by which the nut is turned is normally locked against turning by a device consisting of a plate 19, secured upon one end of a shaft 20, 5 which is journaled in suitable bearings 21 upon the face of the door, said shaft having an operating-lever 22 connected therewith. When the lever 22 is in its elevated position, (shown in full lines, Figs. 1 and 2,) the plate 10 19 is opposite the face of the key and the latter cannot be turned. When the lever is drawn outward, as shown in dotted lines, Fig. 2, and then downward to its full extent, the plate is moved away from the key and the 15 latter may be operated to turn the nut. It is therefore impossible to send in a fire-alarm without first pulling the lever downward, and this downward movement of the lever is caused to operate suitable local alarms to call 20 attention to the person who is about to send in the fire-alarm. Several such local alarms are illustrated in the drawings, one or all of which may be employed.

As shown in the drawings, a pair of pins 25 are arranged upon the free end of the lever 22, and these pins are adapted to engage eyes 26 upon a pair of spring-pressed rods 27 in the forward part of a housing B, arranged upon the top of the box, and similar eyes 28 30 upon a pair of spring-pressed rods 29 in the rear of the rods 27, suitable openings 30 being formed in the front of the casing to permit the pins to pass through when the lever is raised. Perforated cross-pieces 31 and 32 35 are arranged within the housing to guide the rods, and each rod is provided with a collar 33, between which and the support 31 are arranged springs 34, surrounding the rods and tending to force them upward. A resetting- 40 slide 35 is arranged upon the front of the housing, and upon the inner face of this slide is arranged a projection 36, which extends over the collars 33. By moving the slide downward the projection 36, bearing against 45 the collars on the rods, forces the latter downward against the action of the springs until the eyes are brought opposite the openings 30, when the rods may be locked with their springs compressed by bringing the lever 22 50 into the vertical position, the pins 25 passing through said eyes. The spring-pressed rods may be used to operate local alarms of various kinds. As shown in the drawings, in the top of the housing B, above the forward pair 55 of rods 27, are arranged nipples 37, adapted to receive blank cartridges, which are exploded by the impact of the rods 27 when released by the outward movement of the operating-lever 22. Above the housing B is arranged a chamber C, into which the ends of 60 the rear rods 29 protrude when released. This chamber is adapted to hold vessels containing different chemicals which ignite when mixed, which vessels when the rods 29 65 are released are punctured or broken thereby, and a light is thus produced. The openings in the bottom through which the rods pro-

trude are surrounded by bushings 38, projecting upwardly around the rods, so that the liquid in the bottom of the chamber will not 70 escape through the openings. The cap or cover 39 of the chamber C is connected by a rod 40 to a cross-piece 41, which is carried by the rods 29, and when said rods are released to break the bottles containing the chemicals 75 the cap is simultaneously raised, so as to permit the flame to pass outwardly and illuminate the fire-alarm box and vicinity and draw attention to and expose the person turning in the alarm. A wire-netting 42 is preferably 80 placed over the stationary part 43 of the chamber in order to prevent particles of glass, &c., from being thrown out when the device is operated. The slide 35 is normally locked in its upper position by a bolt or lock 44, operated by a key which is kept in the possession of the inspector or other official who has occasion to examine and reset the apparatus or by a permutation-lock. When it is desired to reset the device after operation, the slide 90 is unlocked and depressed, as previously described. The eyes in the rods are brought into position where they will be engaged by the pins on the operating-lever when the latter is in its vertical position. The slide is 95 then returned to its normal position. If after the apparatus has been set it is desired to make an inspection without sounding the alarm or igniting the chemicals, the inspector unlocks and lowers the slide and locks it in 100 its lowermost position by turning the bolt 44 with his key into the bolt-hole 45. This prevents the upward movement of the rods, and the operating-lever may then be withdrawn and the key 19 turned to unlock the box. 105

In addition to the alarm and illuminating devices already described or in lieu of the former a whistle may be operated by the downward movement of the lever. In Fig. 1 upon the face of the box-door is shown a 110 whistle 46, connected by a tube 47 to the interior of an air-tight casing 48. This casing is provided with a screw-cap 49 at its upper end, which may be removed for the purpose of inserting a steel capsule 50 or other vessel 115 containing highly-compressed air or gas. In the lower end of the casing is fitted a stuffing-box 51, through which operates a pointed pin or rod 52, which is movable vertically by means of a cam 53 upon a shaft 20. When 120 the lever 22 is pulled down, the cam forces the pin 52 upward, and the latter punctures the capsule, thus liberating the gas, which blows the whistle. A perforated casing 54 is arranged around the casing 48 in order to 125 prevent tampering with the parts. Capsules may be removed or inserted by unlocking and lifting the cover 55 and removing the cap 49. In order to inspect the interior of the box without operating the alarm devices 130 the cap 49, which bears upon the capsule, may be loosened or removed, and the upward movement of the pin 52 will then not puncture the capsule. The whistle may be operated

in other ways. In Fig. 9, for instance, the inner end of the tube 47 bears against a hollow plunger 56, which is carried upon a spring-rod 27^a, operated in the same manner as the spring-rods in the previously-described figures. This plunger extends through an opening in the bottom of the casing 48 and is closed at its lower end. An opening 57 is formed in the side of the plunger, and when the rod moves upward the air passes through said opening and pipe 47 to the whistle. In this arrangement the casing 48 is kept filled with compressed air by means of a pump, which may be attached to the inlet-pipe 58. 15 As shown, the parts are protected by means of a perforated outer casing 54^a.

In Figs. 7 and 8 the improved threaded locking device is shown in connection with an alarm-box of the kind in which it is necessary to break a glass plate in order to obtain access to the lock. For such boxes the nut 15^a upon the front of the door is inclosed by the glass casing, and the noise caused by the breaking of the glass will call attention 25 to the person sending in the alarm. The nut is provided with wings or projections 17^a, by which it may be turned, and where it is desired to attach other alarm devices a lever like the lever 22 may be arranged to engage 30 said projections and prevent turning of the nut until the local alarm is sounded. The interior construction of the nut and threaded stud for moving the cam-piece 9 are substantially the same as that shown in Fig. 3.

35 The nut which engages the stud upon the cam-block may be of any desirable form having a surface adapted to engage the locking-lever, or, if desired, the stud connected to the cam-block may be made tubular and internally threaded, thus constituting a nut, while the part which is shown as a nut in the drawings may be a threaded stud engaging said tubular part, this being merely a reversal of the arrangement shown. In the claims the 40 part which is turned to move the cam will be referred to as a "knob," whatever its form may be.

Having described my invention, what I claim, and desire to secure by Letters Patent 45 of the United States, is—

1. In a fire-alarm box, the combination with a door and a fastening device therefor, of a knob for operating said fastening device, a locking device arranged to lock said knob against turning, and an alarm constructed and arranged to be operated by said locking device when the latter is moved to unlock the knob.

2. In a fire-alarm box, the combination with a door, and a fastening device adapted to lock and unlock the door and arranged to cause delay in opening the same, of a locking device arranged to lock and unlock said fastening device, and an alarm constructed and arranged to be operated by said locking device when the latter is moved to release the fastening device.

3. In a fire-alarm box, the combination with a door and a fastening device therefor, of a knob for operating said fastening device, a lever arranged to lock said knob against turning, and an alarm constructed and arranged to be operated by said lever when the latter is moved to unlock the knob. 70

4. In a fire-alarm box, the combination with the door, of a lock for the door, a device for operating the lock, and means for locking said device and for operating an alarm when said device is released, said lock-operating device being so constructed as to delay the opening of the door for a suitable period of time after said device is released. 75

5. In a fire-alarm box, the combination with the door, of a lock for the door, a device for operating the lock and mechanism for locking said device and for operating sounding and illuminating alarms when said device is released, said lock-operating device being so constructed as to delay the opening of the door for a suitable period of time after said mechanism is released. 80

6. The combination with a fire-alarm box and a door therefor, of a fastening device for said door, a knob and threaded connections between said knob and said fastening device 95 whereby several turns of the knob are required to release the fastening device, an alarm and mechanism for operating the alarm constructed and arranged to prevent the turning of the knob until said alarm mechanism is moved to operate the alarm. 100

7. In a fire-alarm box, the combination with a door, and an alarm, of a lock for the door, a fastening device including a knob requiring several turns to unlock the door, and a device for locking the knob, said knob-locking device being arranged to operate the alarm when moved to unlock the knob. 105

8. In a fire-alarm box, the combination with the door, a knob, and a fastening device requiring several turns of the knob to unlock the door, of a device for locking the knob, and means operated by said knob-locking device for illuminating the vicinity of the box when said device is moved to unlock the knob. 110

9. In a fire-alarm box, the combination with the door, a knob, and a fastening device requiring several turns of the knob to unlock the door, of a device for locking the knob, and means operated by said knob-locking device for illuminating the vicinity of the box and sounding an alarm when said device is operated to unlock the knob. 115

10. In a fire-alarm box, the combination with the door, a knob, and a fastening device 120 requiring several turns of the knob to unlock the door, of a device for locking the knob, and one or more spring-pressed rods arranged to be released by said knob-locking device and operate an alarm when said device is moved to unlock the knob. 125

11. In a fire-alarm box, the combination with the door, a knob, and a fastening device requiring several turns of the knob to unlock

the door, of a device for locking the knob, one or more spring-pressed rods arranged to be released by said knob-locking device when the latter is moved to release the knob, and 5 means for locking said rods to prevent their movement when the box is being inspected.

12. In a fire-alarm box, the combination with the door, a knob, and a fastening device requiring several turns of the knob to unlock 10 the door, of a device for locking the knob, one or more spring-pressed rods arranged to be released by said knob-locking device when the latter is moved to release the knob, a slide adjacent to said rods arranged to reset the 15 springs, and means for locking said slide in two positions.

13. In a fire-alarm box, the combination with the door, a knob, and a fastening device

requiring several turns of the knob to unlock it, of a lever arranged to lock and release the 20 knob, and cartridge-exploding devices arranged to be released by the movement of said lever.

14. In a fire-alarm box, the combination with the door, and a fastening device there- 25 for, of a lever arranged to lock said fastening device, and a spring-pressed rod arranged to be released by said lever and operate an alarm when the lever is moved to release the fasten- 30 ing device.

In testimony whereof I affix my signature in presence of two witnesses.

LOUDOUN CAMPBELL.
